JACK CHAIN

Russell K. Ulm, Butler, Ind., assignor to Universal Tool & Stamping Company, Inc., Butler, Ind., a corporation of Indiana

Original application Nov. 13, 1962, Ser. No. 236,918. Divided and this application Jan. 23, 1964, Ser. No. 339,698

5 Claims. (Cl. 59—91)

This invention relates to an improved chain adapted particularly for use in connection with vehicle jacks and of such nature as to be capable of quick length adjustment to suit height requirements of the lifting means of the jack with respect to the bumper or other vehicle part to be engaged by the chain.

The present invention constitutes a division out of application Serial No. 236,918, filed November 13, 1962.

A further object of this invention is the provision of a strong, sturdy, flexible chain comprising a plurality of metal links which are pivotally connected together so that the curvature of the chain can be adjusted to suit length conditions.

Other objects and advantages of this invention will be apparent during the course of the following detailed description.

In the accompanying drawing forming a part of this specification and wherein similar reference characters designate corresponding parts throughout the several views:

FIGURE 1 is a plan view of the link type chain.

FIGURE 2 is a side elevation of the chain shown in FIGURE 1; the dot-and-dash line showing the manner in which the links can be adjusted when desired to be placed out of the way to suit length conditions in connection with the appliance with which the chain is to be used.

FIGURE 3 is a vertical cross-sectional view taken through the chain substantially on the line 3—3 of FIGURE 1.

FIGURE 4 is a transverse cross-sectional view taken substantially on the line 4—4 of FIGURE 1.

FIGURE 5 is a transverse cross-section view taken through one of the pintle or pivot hinges adapted to connect adjacent links; the view being taken substantially on the line 5—5 of FIGURE 2.

FIGURE 6 is a cross-sectional view taken substantially on the line 6—6 of FIGURE 2.

FIGURE 7 is a perspective view of one of the links of the chain taken from the under side thereof.

In the drawing, the letter A may generally designate the chain. It is of a type intended to be used with a jack structure such as set forth in United States application Serial No. 236,918, filed November 13, 1962.

The articulated chain structure A is formed of a plurality of links 95. They are preferably formed of rigid metal and each includes relatively divergent side walls 96 shown in FIG. 6 connected by an integral bridging narrow outer wall 97 shown in FIG. 4. The walls 96 extend beyond the side edges of the connecting wall 97 and at these locations they are apertured at 99 to receive hinge pins 100 which connect the various links in pivoted relation, one to the other. The pins 100 have heads 101 at one end and at the other end they are peened at 102 and rest against washers 103. If desired, washers may be placed at both ends of the pins 100 at each outer side of the walls 96. Due to the relative slope of the walls 96, links 95 can be conveniently interfitted, as is shown in FIG. 6, to provide a very compact and economically fabricated structure. The pins 100 are uniformly spaced, and are in parallelism, so that they will accurately fit into a lift retainer such as set forth in United States application Serial No. 236,918, filed November 13, 1962. This lift retainer has a plurality of

2

sockets adapted to receive a plurality of the pins 100. To that end the links form a chain channel entirely open at the bottom of the chain throughout its length with no obstructions to insertion of the lift retainer and its adjustment along the channel throughout the length of the chain. If desired friction pads 104 may be attached on the outer surfaces of the cross walls 97 to prevent marring of bumpers and other vehicle parts with which the chain may come in contact during a lifting operation.

The chain structure at its lower end is provided with a bumper or vehicle frame engaging hook 106 having top ears 107, apertured to pivotally receive the lowermost pin 100a of the lowermost link. The hook side walls are divergently flared as shown in FIG. 1. The end 108 is hooked for engagement beneath a vehicle frame or bumper.

It will be noted that the parts of the chain A are of rigid stamped metal with the exception of the metal hinge pins, and the cushioning pads 104. It will be noted that the plane of the connecting wall 97 of each link is at an angle of 90 degrees with respect to the planes of the side walls 96. The ends of the walls 96 extend appreciably beyond the fore and aft edges of the cross walls 97 in order that the chain links can curve to an out-of-the-way position as is shown in dot-and-dash lines in FIG. 2. It will also be noted that the bottom surface of the bridging walls 97 lie in a plane appreciably spaced from the hinge pins 100 to facilitate mounting of the hinge pins and link upon a lift retainer of the jack structure with which this chain is adapted to be used, such as set forth in application Serial No. 236,918, filed November 13, 1962.

Various changes in the size, shape and arrangement of parts may be made to the form of invention shown, without departing from the spirit of invention or scope of the claims.

I claim:

1. As an article of manufacture a vehicle lifting chain comprising a plurality of pivotally connected links each having a pair of spaced side walls and a bridging wall connected to the outer margins of the side walls at the front part of the chain, said side walls being apertured at each end, and pins extending through said apertures crosswise of the length of the chain and pivotally connecting the links together, said side walls of each link being relatively divergent from end to end to such a degree that the side walls of the link at the closest end spacing of its walls will fit into and between the walls of an adjacent link at its widest spacing of said side walls.

2. A jack chain as described in claim 1 in which the bridging wall of each link is relatively narrow compared to the length of the side walls so that the side margins of the bridging wall of each link terminate appreciably short of the pins which connect adjacent links together.

3. The jack chain described in claim 1 in which the side walls below the cross walls define a channel which is entirely open at the bottom of the chain and unobstructed for attachment of a lift retainer with the exception of said cross pins onto which a lift retainer is adapted to be hooked.

4. The chain described in claim 1 in which the end link of the chain whose side walls are endwise spaced at their greatest width has a hook pivotally connected thereto.

5. As an article of manufacture a vehicle jack chain comprising a plurality of pivotally connected links each comprising a pair of spaced side walls and an integral bridging wall connected to the outer margins of the side walls at the front of the chain, said side walls being apertured at each end at locations entirely beyond the marginal edges of the cross walls, and uniformly spaced pins extending through said aperture crosswise of the length of the chain and pivotally connecting the links together, said

links when in line defining a channel which is entirely open at the rear thereof opposite said cross walls with the exception of said pins which lie and about midway of the depth of the channel throughout the length of said channel.
